UNITED STATES PATENT OFFICE.

ANTON J. HAUG, OF NASHUA, NEW HAMPSHIRE, ASSIGNOR TO IMPROVED PAPER
MACHINERY COMPANY, OF NASHUA, NEW HAMPSHIRE, A CORPORATION OF MAINE

METHOD OF AND APPARATUS FOR SEPARATING FOREIGN MATTER FROM PAPER STOCK.

Application filed November 21, 1919. Serial No. 338,564.

To all whom it may concern:

Be it known that I, ANTON J. HAUG, a citizen of the United States, and a resident of Nashua, county of Hillsborough, and 5 State of New Hampshire, have invented an Improvement in Methods of and Apparatus for Separating Foreign Matter from Paper Stock, of which the following description, in connection with the accompanying drawings, is a specification, like characters on the drawings representing like parts.

This invention relates to methods of and apparatus for separating foreign matter from paper stock and particularly sand, 15 grit, sediment, sawdust, coal, metal, etc. The object of the invention is to provide an improved means for and method of separating such foreign matter providing for an efficient separating action and improved 20 facilities for cleaning without interference with the operation of the process.

These and other objects of the invention will be best understood by reference to the following description when taken in connection with the accompanying illustration of 25 one specific embodiment thereof, while its scope will be more particularly pointed out in the appended claims.

In the drawings:—

30 Figure 1 is a plan view of separating apparatus embodying one form of the invention and adapted to carry out one form of the method;

Fig. 2 is a sectional elevation taken on 35 the line 2—2 in Fig. 1 and showing the separating apparatus therein;

Fig. 3 is an end elevation, partially in section, of the main or body part of the separating apparatus shown in Figs. 1 and 40 2; and

Fig. 4 is a detail showing the flushing openings with their closures withdrawn.

Referring to the drawings and to the embodiment of the invention which is there 45 shown for illustrative purposes, I have there shown a plurality of (and herein two) separating devices which for convenience are arranged parallel with each other and side by side upon the same table or support, but so 50 related to the stock inlet that the stock may be passed through the one or the other at will. While the location of these two separating chambers as shown in the drawings is a convenient one, it will be understood

that other relative positions may be adopted 55 without departing from the spirit of the invention.

The stock is fed to the apparatus through an inlet opening 1 from any suitable inlet pipe (not shown), the two separating devices having the same inlet as will be more fully explained. The two separators are of substantially the same construction and it is necessary to describe the details of one only. Each device comprises a bottom 2 60 provided with sides 3 forming a channel or passage through which the stock flows, the latter entering at the inlet end and emerging at the opposite end where it is delivered to an outlet pipe 4, the outlet pipes for the 65 two separators leading preferably into a common receiving chamber. The outlet ends of the separating chambers are closed by the end walls 5, preventing the escape 70 of the stock except through the outlet, and the opposite ends are closed by the end wall 6. A gate valve 7 hinged upon the casing at 8 is adapted to be moved either to the full line position shown in Fig. 1 where it 75 closes the separating chamber 10 to the inlet, or it may be moved to the dotted line position shown therein where it shuts off communication between the separating chamber 20 and the inlet. When the valve is moved to shut off the separating chamber 80 10 from the inflow of stock, the latter enters the chamber 20 through the inlet opening 21. When it is moved to its opposite position to shut off the chamber 20, the flow 85 of stock is immediately diverted to the separating chamber 10 through the inlet opening 11.

The framework is bound together and stiffened by various suitable cross members 90 30, so that the apparatus resembles in outward appearance two elongated, separate, uncovered, box-like compartments with separate outlets and a common inlet with its controlling valve or gate whereby the incoming stock may be diverted from one to 100 the other at will.

The stock entering whichever chamber is connected with the inlet opening 1, first meets the baffle plate 31 and is compelled to flow through the space beneath the same and 105 immediately comes in contact with the baffle plate or weir 32 arranged transversely across the bottom of the compartment. Between

the plate 32 and a similar but preferably lower plate 33 near the outlet end of the compartment, there is provided a series of riffle plates 34 which are set into the strips 34^a and 34^b lining the side walls of the chamber. The riffle plates are inclined in the direction of flow of the stock and provide a series of intermediate settling chambers in which the heavier sedimentitious material 10 contained therein tends to settle through gravity. Any suitable number of these riffle plates and settling chambers may be provided and preferably, though not necessarily, they are arranged in a descending 15 scale of height so that the highest plates and deepest settling chambers are located near the inlet end.

In the use of this apparatus, the settling chambers in the course of time become filled 20 and clogged with foreign matter; and in order to facilitate its cleansing at suitable intervals, the lining strips 34^b are cut away between the riffle plates to provide lateral outlets 34^c, and the outer side wall 3 of each chamber is provided with one or more lateral openings 35 which open communication 25 between the settling chambers and a flushing passage 36, the latter arranged at the side of the apparatus and formed by 30 the side 3 of the settling chamber, the bottom piece 37 and the side closure 38. Each flushing passage is closed at the ends but communicates near its mid portion with a drain pipe 39 adapted to drain off the 35 cleansing fluid and sediment.

The flushing openings 35 are normally closed by gates or valves 40. While a number of separate openings and separate gates may be employed, herein for convenience a 40 single gate for each side is utilized. The gate or gates 40 controlling the flushing openings are secured to lever arms 41 mounted to move with the rock shaft 42, the latter carried in bearings provided by a 45 series of supporting members 43 fastened to the sides 3 and 38 of the flushing passage. The rock shaft is also secured (see Figs. 3 and 4) to an arm 44 carrying at its upper end the segmental worm gear 45 adapted to mesh with the worm 46 the shaft of which is journaled in the bracket 47 and carries at its end the wheel 48. By turning the hand wheel 48, the rock shaft 42 may be turned through the described 50 worm gearing and the gate or gates 40 moved to close the openings 35 (as shown in Fig. 3) or to open the same (as shown in Fig. 4). When the apparatus is in operation, the gates are closed as shown in 55 Fig. 3. When the apparatus is out of operation and it is desired to cleanse it, the gates are opened as shown in Fig. 4 and a stream of flushing water turned into the various settling chambers, which washes the 60 accumulated sediment through the openings 65

35 into the flushing passages 36 and down the drain pipe 39.

While the settling chambers might be provided with horizontal bottoms, to facilitate the cleansing of the settling chambers a bottom plate 49 is preferably interposed between the riffle plates 34 and the bottom plate 2, the intermediate bottom plate 49 sloping laterally from the inner wall of the separating chamber to the outer wall thereof, thereby 70 providing a laterally sloping bottom for each settling chamber which slopes toward the flushing opening and assists in draining the sediment therethrough when the flushing water is turned into the apparatus. 75

In the operation of a separator of the kind described, it is desirable to clean the apparatus from time to time with as little interference as possible with its normal operation. In apparatus intended for this purpose, it is usually necessary to perform the cleansing operation on nights or Sundays or, where this is not possible, to shut down the apparatus for a substantial period and interrupt its operation. In the described 80 form of apparatus, not only are greatly improved means provided for facilitating the cleansing but through the utilization of the two cooperatively related separating devices the flow of stock may be diverted from one chamber to the other without an interruption or even the slightest disturbance of the flow of the stock, so that the necessary frequent cleaning will not cause agitations 85 and fluctuations in the process of sedimentation. 90

It is highly desirable that the flow of the stock proceed smoothly and uninterrupted for correctly carrying out the sedimentation, and such smooth flow is secured by the described form of apparatus. 105 As soon as it becomes necessary to clean that side of the device which is in use, the gate valve is shifted, diverting the stock flow into the other side of the apparatus without agitation or disturbance of the flow. The hand wheel on the side of the table which has just been cut out of use is then moved, opening the settling chambers to the flushing passage, and flushing water forced in. The sloping bottoms of the settling chambers 110 quickly wash away the collected sediment so that the gates can again be closed tightly and the apparatus is again in condition for use. The apparatus may therefore be cleansed as frequently as desired 115 without interrupting or disturbing the continuing flow of the stock and the complete separation of the foreign matter therefrom. The cleansing can be done with a minimum expenditure of time and labor and may be effected at any time during the working 120 hours or otherwise.

While I have herein shown and described for purposes of illustration one specific form of the invention, it will be understood 125

that the same is not limited to the specific construction or to the details herein shown or to the form or relative arrangement of parts, but that extensive deviations may be made therefrom without departing from the spirit thereof.

Claims:

1. An apparatus for separating foreign matter from paper stock presenting a passage for the unidirectional flow of stock provided with a plurality of settling chambers or recesses to receive sediment, each chamber having a valved opening to remove the accumulated sediment therefrom and said valved openings being collectively operable.
2. An apparatus for separating foreign matter from paper stock presenting a passage for the unidirectional flow of stock provided with a plurality of settling chambers, each having a lateral valved opening to remove the accumulated sediment therefrom and said valved openings being collectively operable.
3. An apparatus for separating foreign matter from paper stock presenting a passage for the flow of stock provided with riffle plates forming a plurality of settling chambers and lateral valved openings to remove the accumulated sediment therefrom, said settling chambers having inclined bottoms sloping toward the said lateral openings and said valved openings being collectively operable.
4. An apparatus for separating foreign matter from paper stock having a plurality of settling chambers provided with sediment discharge openings normally closed and means for simultaneously opening said discharge passages.
5. An apparatus for separating foreign matter from paper stock presenting a passage for the flow of stock, a plurality of riffle plates providing intermediate settling chambers having inclined bottoms sloping toward the side and having also openings at the side of the lower end of each chamber and movable closing means for the openings.
6. An apparatus for separating foreign matter from paper stock having a series of riffle plates with intermediate settling chambers over which the stock may be flowed, said settling chambers being provided with cleansing openings and one or more normally shut closures therefor, means for simultaneously moving said closures, the same comprising a rock shaft connected to the closures and a device for turning the rock shaft.
7. A device for separating foreign matter from paper stock having a plurality of pas-
8. An apparatus for separating foreign matter from paper stock having a plurality of passages for the flow of stock, each provided with one or more settling chambers, means to direct the flow of stock to either one of said passages to the exclusion of the other and without interruption in the flow thereof, whereby one may be utilized for separation while the other is being cleaned.
9. An apparatus for separating foreign matter from paper stock presenting a plurality of passages for the flow of stock, each provided with one or more settling chambers, said settling chambers having cleansing openings with cleansing means therefor, means for directing at will the flow of stock to one of said passages to the exclusion of the other whereby one may be utilized while the other is being cleaned.
10. An apparatus for separating foreign matter from paper stock presenting a plurality of passages for the flow of stock; each having one or more settling chambers, said settling chambers having each a lateral cleansing opening and an inclined bottom sloping laterally toward said opening, closing means whereby said openings may be opened or closed at will and means for directing at will the flow of stock to either of said passages to the exclusion of the other whereby one may be utilized for separation while the other is being cleaned.
11. A sand separator for paper stock comprising a plurality of passages with one or more separating chambers in each, a common inlet and a valve for directing the stock into either passage at will.
12. A sand separator for paper stock having a plurality of passages for the flow of the stock presenting each one or more settling chambers, an inlet and a gate valve for directing the flow of stock to either passage at will and without interruption or disturbance of the flow.
13. The method of separating foreign matter from paper stock which consists in removing the foreign matter by sedimentation from the flowing stock while flowing through a given path, diverting the flow of the stock without interruption to a second path and removing the accumulated sediment from the first path while carrying on the process of sedimentation in the second path.

In testimony whereof, I have signed my name to this specification.

ANTON J. HAUG.
